(57) **CLAIM**

The ornamental design for a multi-compartment detergent unit dose, as shown and described.

DESCRIPTION

FIG. 1 is a top perspective view of a first embodiment of a multi-compartment detergent unit dose showing our new design;

FIG. 2 is a top view of the design of FIG. 1;

FIG. 3 is a bottom view thereof of FIG. 1;

FIG. 4 is a front view thereof of FIG. 1;

FIG. 5 is a rear view thereof of FIG. 1;

FIG. 6 is a right side view thereof of FIG. 1; and

FIG. 7 is a left side view thereof of FIG. 1.

FIG. 8 is a top perspective view of a second embodiment of a multi-compartment detergent unit dose showing our new design;

FIG. 9 is a top view of the design of FIG. 8;

FIG. 10 is a bottom view thereof of FIG. 8;

FIG. 11 is a front view thereof of FIG. 8;

FIG. 12 is a rear view thereof of FIG. 8;

FIG. 13 is a right side view thereof of FIG. 8; and

FIG. 14 is a left side view thereof of FIG. 8.

FIG. 15 is a top perspective view of a third embodiment of a multi-compartment detergent unit dose showing our new design;

FIG. 16 is a top view of the design of FIG. 15;

FIG. 17 is a bottom view thereof of FIG. 15;

FIG. 18 is a front view thereof of FIG. 15;

FIG. 19 is a rear view thereof of FIG. 15;

FIG. 20 is a right side view thereof of FIG. 15; and,

FIG. 21 is a left side view thereof of FIG. 15.

In the drawings, the broken lines illustrate portions of the article which form no part of the claimed design.

In FIGS. 15 through 21, the grey scale shading represents a contrast in appearance.

1 Claim, 15 Drawing Sheets
